UNITED STATES PATENT OFFICE

107,804

DESIGN FOR A COMBINED LAMP AND SMOKING STAND OR THE LIKE

Victor Stanzel, Schulenburg, Tex.

Application August 2, 1937, Serial No. 70,781

Term of patent 7 years

To all whom it may concern:—

Be it known that I, Victor Stanzel, a citizen of the United States, residing at Schulenburg, in the county of Fayette and State of Texas, have invented a new, original, and ornamental Design for a Combined Lamp and Smoking Stand or the like, of which the following is a specification, reference being had to the accompanying drawing, forming a part thereof.

Figure 1 is a side elevational view of a combined lamp and smoking stand showing my new design, and

Figure 2 is an elevational view of the front end thereof with the base portion omitted.

The stand is intended to support either a light globe or a cigarette lighter, each having the same identical exterior appearance.

The dominant feature of the design resides in the parts shown in full lines.

I claim:—

The ornamental design for a combined lamp and smoking stand or the like as shown and described.

VICTOR STANZEL.
